UNITED STATES PATENT OFFICE.

AXEL NASHLUND, OF MARQUETTE, MICHIGAN.

FACTORY AIR-CLARIFIER AND FUME-COLLECTOR.

1,371,205.

Specification of Letters Patent. Patented Mar. 8, 1921.

Application filed February 25, 1920. Serial No. 361,281.

To all whom it may concern:

Be it known that I, AXEL NASHLUND, subject of the King of Sweden, residing at Marquette, in the county of Marquette, State 5 of Michigan, have invented certain new and useful Improvements in Factory Air-Clari-fiers and Fume-Collectors; and I do hereby declare the following to be a full, clear, and exact description of the invention, such as 10 will enable others skilled in the art to which it appertains to make and use the same.

This invention relates primarily to a method and apparatus for protecting employees of factories or plants from the injurious effects of the different chemicals and 15 gases and obnoxious and injurious odors which escape during the production of certain products, and the preparing and concentrating of certain materials with partic- 20 ular reference to the manufacture of sulfuric acid, alcohol, creosote, formaldehyde and the like. The invention also contem- plates a recovery of the escaping fumes and the subsequent utilization thereof. Many 25 chemicals and gases formed in the making of the various substances are very injurious to the health of those engaged in the manu- facture of such products, effecting not only the skin, but the throat and various other 30 organs of the body. These fumes are also detrimental to vegetation in the vicinities of the factories or plants and oftentimes result in the total extinction thereof. It is to ob- 35 viate the foregoing injurious effects above related that the apparatus, to be hereinafter more fully referred to, has been devised, forming the subject of this application, which apparatus will collect and remove all 40 gaseous fumes and either dispose of them into a sewer or the like, or collect and re- 45 cover the same for further disposition or use.

Briefly stated, the invention comprises a metallic casing or shell adapted to completely inclose a still, column, retort, or the like, used in the manufacture of the different acids and chemicals, from which it is desired to collect and recover the escaping fumes. This casing is constructed of a series of over-lapping doors, or sections, 50 forming the sides thereof, and a conical shaped top, which extends slightly beyond the sides leaving a space therebetween. Sup- 55 porting this top and arranged diametrically opposite are two vertical suction pipes, or standards, to which the doors are hinged.

These pipes are provided with perforations along their inner sides extending from top to bottom, said perforations gradually increasing in size as they approach the top. This increase in size of the holes increases 60 the circulation caused by the fan, but is only necessary where a very high still or column is used. These suction pipes ex- 65 tend beyond the top of the casing and are connected to a pipe running to a fan. The top of the casing is also provided with a pipe outlet which is connected to this same pipe.

Detachably secured to the outside of the column or still are suction pipes arranged 70 on each side of the doors or closures in said still in order to catch the fumes that es- 75 cape from these closures. These pipes are grouped at the top and center of the column and their upper ends are preferably en- 80 larged or funnel-shape and when in posi- 85 tion are under the pipe outlet in the top of the casing.

The fumes that are drawn off, during the 80 operation of the device, by the fan, are con- ducted to a receiving chamber or receptacle, 85 preferably placed under ground. This chamber is provided with outlet openings, one connected to a sewer or the like, provid- 90 ing a discharge or waste, and the other con- 95 nected to a pipe line, which line is in turn connected to a series of receptacles or tanks. If the resulting product or liquid produced by the condensing of the fumes on the way to the receiving chamber is not desired, it 100 may be discharged through the waste pipe into the sewer, but if it is desired to save said product it can be used to a good ad- vantage by drawing it off into the tanks above mentioned. These tanks ordinarily will contain a quantity of a similar liquid, but of a much weaker condition and the liquid drawn off from the receiving recep- 105 tacle can be used advantageously for in- creasing the strength of this weaker liquid to the desired degree.

The apparatus particularly adapted for carrying on this operation or process is illus- trated in the accompanying drawings in which,

Figure 1 shows the general arrangement of the complete apparatus.

Fig. 2 shows a view partly in elevation and partly in section of the still inclosed by the casing.

105

110

Fig. 3 is a top plan view, and

Fig. 4 is a view of the main part of the apparatus with the cover removed.

Referring to the drawings in detail in which like numerals refer to like parts throughout the several views, 1 is the casing, made in accordance with this invention, surrounding a still or the like 2. This casing is provided with diametrically arranged vertical standards 3 anchored to the ground by suitable supports 4. Supported from the top of the standards is a cover 5 for the casing, which cover is preferably positioned above the casing, allowing a small annular opening between the top edge of the casing and the bottom edge of the cover. It will be also noted that the casing is supported slightly above the ground level. These standards not only act as supports, but are provided with openings 6 on their inner sides and are connected to a pipe 7 running to an exhaust fan 8. An opening is provided in the cover 5 to which is connected an exhaust pipe 9', also connected to fan 8 by way of pipe 7, and positioned between pipe 7 and fan 8 is a regulating valve 8'.

The casing 1 is preferably made circular and is constructed of a series of doors or sections 9, said doors being hinged at a point adjoining the standards 3 and are provided with fastening means 10. In one or more of the hinged sections there is provided sight openings 11 for the purpose of examining the inside of the apparatus when desired without opening the casing. In the cover 5 there is an opening provided with a hinged door 12, allowing the insertion of a pipe running to the still for feeding said still.

Secured to the inside of the casing by suitable means are a series of flaps or beaters 13, preferably made of wool or similar material, to withstand the action of the acid fumes. These flaps or beaters are arranged adjoining the openings in the casing and around the various pipe outlets for the purpose to be hereinafter referred to.

Detachably supported on the still 2 are pipes 14 provided with holes or openings 15. These pipes are placed adjoining the doors or closures 16 of the still, grouped at the top thereof and secured together by a clamp or similar device 17. The lower ends of these pipes are closed and the upper ends thereof are enlarged or funnel-shape as shown at 18. It will be noted that the enlarged ends of these pipes are directly beneath and adjoining the outlet pipe 9' of the cover 5. Connecting the fan 8 with a receiving chamber 19 is a pipe or conduit 20. This chamber is placed well under ground and is surrounded with a substantial layer of charcoal and may be made of wood lined with lead or the like, but it is preferably made of vitreous material. The pipe 20 enters the chamber and extends well into

the same and the end of said pipe is provided with apertures or openings 21. At a point substantially at the bottom of the chamber is an outlet or waste pipe 22, provided with a valve 23 leading to a sewer or other waste receiving means. Positioned slightly above the bottom of the chamber is an outlet pipe 24 connected to a supply line 25, which line is in turn connected to a series of receiving tanks 26 by suitable valves 27. It is to be understood that the various parts of this apparatus, subject to the action of the fumes and acids, are to be constructed of material to withstand the action of said fumes or acids.

During the operation of the apparatus the casing 1 being in position surrounding the still 2 and the various exhaust pipes being connected to the fan 8, the fan is set in motion creating a suction in the pipes 7 and 9' and standards 3 and at the same time in view of the fact that the pipes 14 are directly beneath the exhaust pipe 9', a suction will also be created in said pipes 14. As the air is exhausted from these pipes, a circulation is maintained within the casing causing the agitation of the flaps or beaters and keeping the air within said casing in motion. As hereinbefore stated, these flaps or beaters are positioned adjacent the openings in the casing and are so placed to prevent the gas from escaping at these openings by driving said gases therefrom. The pipes 14 being arranged near the doors or closures of the still, most of the gas escaping from around these closures will be collected and taken care of by said pipes and exhausted from the top thereof through the pipe 9'. All gases or fumes which are not completely exhausted by these pipes are retained by the casing 1 and exhausted therefrom through the openings 6 in the standards 3. As hereinbefore stated, the standards 3 and central exhaust 9' are both connected to a common suction pipe 7 running to the fan 8. As the fumes and gases are withdrawn from the casing and around the still by the fan 8, they are conducted to a receiving chamber 19, being condensed on the way, and the resulting liquid can be disposed of through the waste pipe into the sewer.

If it be desired to save this resulting liquid, the same can be conducted to receiving tanks containing similar liquid but of a reduced strength, the said resulting liquid being advantageously conducted into said tanks to increase the strength of said liquid contained therein to a desired degree. Obviously, this liquid may be recovered in empty tanks provided for the purpose instead of being used to strengthen a similar liquid of a weaker strength.

Applicant has only shown his apparatus in connection with a single still or column, but it is to be understood that in the ordi-

nary practice these stills or columns are arranged in numbers and under these conditions, of course, it is simply a matter of duplicating the arrangement for each still 5 or column. Of course, it will be apparent that additional tie rods or braces may be used for supporting the casing where it will be found necessary in a large apparatus.

What I claim is:

10 1. An apparatus for the recovery of fumes from stills, columns, retorts, and the like, comprising a casing surrounding said still, column, or retort, means for maintaining a circulation of air through said casing, and 15 means of agitating the air within said casing.

2. An apparatus for the recovery of fumes from stills, columns, retorts, and the like, comprising a casing surrounding said still, 20 column, or retort, means for maintaining a circulation of air through said casing, and flexible flaps or beaters for agitating the air within said casing.

3. An apparatus for the recovery of fumes 25 from stills, columns, retorts and the like, comprising a casing surrounding said still or column, means carried by said still or column for collecting the fumes escaping therefrom and means for creating a suction 30 in said fume collecting means.

4. An apparatus for the recovery of fumes from stills, columns, retorts and the like, comprising a casing therefor, means carried by both the casing and the still or column 35 for collecting the fumes escaping from said still or column and means for creating a suction in said fume collecting means.

5. An apparatus for the recovery of fumes 40 from stills, columns, retorts, or the like, comprising a casing therefor, means located near the closures in said stills for collecting the fumes escaping therefrom, means associated with the casing for agitating the air and fumes within said casing and means for 45 creating a suction in both the casing and the fume collecting means carried by the still.

6. An apparatus for the recovery of fumes 50 from stills, columns, retorts, and the like, comprising a casing therefor, perforated pipes carried by the still, located near the closures thereof, perforated pipes positioned within the casing and means for creating a suction in both sets of pipes.

7. In an apparatus for the recovery of 55 fumes, the combination with a still or the like, of a cylindrical casing, hollow standards for said casing, base supports for said standards, the bottom edge of said casing elevated above said base support, a cover or top for said casing, an annular space separating the casing from the top, perforations in said standards and means for creating a suction in said standards.

8. In an apparatus for the recovery of 60 fumes, the combination with a still or the

like, of a cylindrical casing therefor, hollow standards for said casing, base supports for said standards, the bottom edge of said casing elevated above said base support, a cover or top for said casing, an annular 70 space separating the casing from the top, means associated with the casing for agitating the air and fumes therein, perforations in the standards, and means for creating a suction in said standards.

75

9. In an apparatus for the recovery of fumes, the combination with a still or the like, of a cylindrical casing therefor, hollow perforated standards for said casing, base supports for said standards, the bottom edge of said casing elevated above said base support, a cover or top for said casing, an annular space separating the casing from the top, an outlet in the top of said cover, an exhaust pipe connected with said outlet, 85 pipes connecting said outlet pipe and hollow standards, and means for creating a suction in said pipes.

10. In an apparatus for the recovery of fumes, the combination with a still or the like, of a cylindrical casing therefor, hollow perforated standards for said casing, base supports for said standards, a cover or top for said casing, an outlet in the top, exhaust pipes connecting said outlet and hollow standards, perforated pipes carried by the still adjacent the closures thereof, extending upwardly and converging at the top of said still communicating with the exhaust outlet in the top of the casing and means for 100 creating a suction in said exhaust pipes.

11. In an apparatus for the recovery of fumes, the combination with a still or the like, of a cylindrical casing therefor, said casing comprising hinged sections, a cover 105 or top for said casing, pipe openings in said top, flaps or beaters on the inside of said casing encircling said pipe openings and adjacent the joints of the hinged sections, and means for causing a circulation of air 110 through the casing and the operation of the flaps or beaters.

12. In an apparatus for the recovery of fumes, the combination with a still or the like, of a cylindrical casing therefor, said 115 casing comprising overlapping hinged sections, a cover or top for said casing, pipe openings in said top, perforated pipes carried by the still adjacent the closures thereof extending upwardly and converging at 120 the top of said still, communicating with one of the pipe openings in the top of the casing, flaps or beaters on the inside of said casing encircling said pipe openings and adjacent the joints of the hinged sections, and means for creating a suction in the pipes 125 carried by the still, causing a circulation of air through the casing, and the operation of the flaps or beaters.

13. In an apparatus for the recovery of 130

fumes, the combination with a still or the like, of a cylindrical casing therefor, provided with sight openings, said casing comprising overlapping hinged sections, hollow 5 perforated standards for said casing, base supports for the standard, the bottom edge of said casing elevated above said base support, a cover for the casing, an outlet in said cover, an annular space separating the casing from the cover, perforated pipes carried by the still adjacent the closures thereof extending upwardly and converging at the top of said still communicating with the outlet in the cover, flaps or beaters on the 10

inside of said casing encircling said outlet 15 and adjacent the joints of the hinged sections, and an exhaust fan for creating a suction in the hollow standards and the pipes carried by the still, causing a circulation of air through the casing and operating the 20 flap or beater.

In testimony whereof I affix my signature in presence of two witnesses.

AXEL NASHLUND.
